UNITED STATES PATENT OFFICE

WILLIAM J. SCHLACKS, OF CHICAGO, ILLINOIS, ASSIGNOR TO RYAN MNFG. CORPORATION, OF CHICAGO, ILLINOIS, A CORPORATION OF ILLINOIS

ROAD GRADER

Application filed July 28, 1928. Serial No. 295,912.

My invention relates in general to road graders and has for its broad object the provision of an improved road grader of simplified construction.

5 The type of grader to which my invention is particularly applied, is illustrated in the copending application of Daniel C. Hinds, Serial No. 689,416, filed January 30, 1924, now Patent No. 1,732,892, and Owen E. Grigsby, 10 Serial No. 110,335, filed May 20, 1926. These graders comprise a wheeled carriage with a tiltable main frame and a drawbar having a universal joint connection thereto. The drawbar has a number of adjustments including means for lifting either the front or rear end thereof, means for shifting the drawbar sideways, and a large number of compound movements resulting from proper control of the lifting and side shifting mechanisms.

20 The present invention relates specifically to control mechanisms for the drawbar particularly the mechanism for lifting the front end thereof and for shifting the mold board and frame sideways. It relates also to certain refinements of structure which improve the flexibility of performance, eliminate possible weak points in the structure, and reduce manufacturing and maintenance costs.

25 The principal specific object of the invention is to improve the drawbar control mechanism.

Another object is to modify the drawbar control so that a back sloping operation may be performed on either side of the grader.

30 Another object is to improve the mold board side-shifting mechanism.

Another object is to improve the mechanism for lifting the front or pivoted end of the drawbar.

35 Another object is to provide an improved connection between the drawbar and main frame which can be easily assembled.

40 There are other specific features and objects of my invention which will become apparent as the detailed description progresses and will appear in the accompanying drawings illustrating one embodiment wherein,

45 Fig. 1 is a side elevational view partly broken away showing the drawbar with a

portion of the main frame from which it is suspended;

Fig. 2 is a sectional view along the line 2—2 of Fig. 1 showing the drawbar in plan;

Fig. 3 is an irregular sectional view along the line 3—3 of Fig. 1;

Fig. 4 is a fragmentary plan section along the line 4—4 of Fig. 3;

Fig. 5 is a detail of the trolley carriage with the crank mechanism shown in elevation, the view being a section along the line 5—5 of Fig. 3;

Fig. 6 is a vertical longitudinal elevation section through the drawbar lift mechanism showing the front post of the main frame and its connection to the front axle, and

Fig. 7 is a sectional plan view through the drawbar lift mechanism along the line 7—7 of Fig. 6.

In order that the improvements forming the subject matter of the present invention may be clearly understood, the general arrangement existing between the drawbar and other portions of the grader will first be described. The grader comprises a main frame 10 suitably secured to the rear wheel carriage and having a front post 11 with a ball 12 at the bottom thereof suitably supported in a front axle 13 on the ends of which are wheels 14'. In this type of grader, the wheels are 15 tiltable with respect to the axle; the main frame is also tiltable; and the axle may be turned about the ball 12 as a pivot to change the direction of travel of the grader. The frame carries a central power-house for operating the various adjustments but it is obvious that the controls may be operated from any source of power, without departing from the spirit of the invention.

Suspended below the grader frame, is a 20 drawbar 14 carrying the circle frame 16 to which is secured a mold board 17. The drawbar is secured at its front end in the main frame post and a mechanism is provided for raising and lowering the front end with respect to said post. A great many different forms of mechanism could be provided for this purpose, but I have developed a structure which is greatly superior to anything 25 of this nature heretofore employed.

The drawbar itself consists of two longitudinal members 18 and 19, preferably Z-beams, forming a V suitably secured at the apex to an apex member or stem 21 which is provided with a ball 22. At the rear of the drawbar suitable braces are provided to maintain the proper relative position of the longitudinal beams and for mounting control members and the like thereto.

Referring now more particularly to the front of the drawbar, the main frame post 11 has a slot 23 into which the stem is adapted to project and a cross piece or block 24 formed of two parts held together by bolts 26, surrounds the ball 22 and holds it in loosely so that it may be moved with respect thereto. The cross piece has a pair of projections 27 and 28 at the front thereof between which a worm 29 is supported, the worm being free to move vertically on a shaft 31 which is carried by a post cover 32. The shaft 31 and worm 29 are provided with keyways, and a key 30 is held in the worm keyway and extends loosely into the key-way in the shaft 31. The post cover has gear teeth 33 on the inside thereof constituting a rack so that rotation of the shaft 31 will cause worm 29 to turn in engagement with the rack and draw itself with the cross piece 30 and drawbar either upwardly or downwardly depending upon the direction of rotation. As a drive for the shaft 31, a bevel gear 33 is provided at the top thereof meshing with a second bevel gear 34 on a shaft 36 suitably journaled in the top of the main frame post. A shaft 36 has a universal joint 37 to a drive shaft 38 leading to a suitable source of power at the rear of the grader.

The projections 27 and 28 at the front of the cross piece are so disposed that the shaft 31 can be inserted therebetween. This shaft is carried by the cover 32 and this simplifies the assembly considerably. The cover with the square shaft and worm 29 together with the bevel gear 33 at the top thereof, are assembled as a separate unit. As another unit the cross piece 24 is assembled in the front post with the ball 22, and the shaft 36 and the bevel gear 34 are assembled in the top of the post. All that is necessary to complete the assembly then, is to place the post cover on the post so that the gears 33 and 34 mesh and the square shaft extends between the projections on the cross piece with the worm 29 between the upper and lower pairs of projections.

The rear end of the drawbar is provided with a supporting mechanism adapted to be controlled for raising and lowering or otherwise adjusting the drawbar about the front pivot. The support for this mechanism comprises a pair of parallel I-beams 41 and 42 secured transversely of the frame. On the upper part of these I-beams is secured a pair of brackets 43 and 44 in which shafts 46 and

47 are journaled. The shafts have secured thereto at one end, cranks 48 and 49 which are attached to one end of links 51 and 52, the lower ends of said links being pivotally connected to brackets 53 and 54 carried by the drawbar members 18 and 19 respectively. The other ends of the shafts 46 and 47 have secured thereon worm gears 56 and 57 which mesh with worms 58 and 59 carried by vertical shafts 61 and 62 suitably journaled in a portion of said first mentioned brackets. These vertical shafts have at the upper end thereof, worm gears 63 and 64 which mesh with and are driven by worms 66 and 67. These worms are keyed to shafts 68 and 69 also suitably journaled in the brackets aforesaid and connected by universal joints 71 and 72 to drive shafts 73 and 74 leading to a suitable source of power at the rear of the grader.

With this construction, it is apparent that the links 51 and 52 carried by the cranks support the rear end of the drawbar, and rotation of the cranks serves to position the rear end of the drawbar vertically. These cranks may be operated in unison in the same direction or they may be made to take opposed positions to tilt the drawbar sideways, if no other controlling mechanism whatsoever were provided. I incorporate with this construction however, an improved side thrust mechanism by means of which the drawbar may be controlled when the frame is in proper position to dispose the mold board in a vertical position outside the line of draft of the grader in which position it may be used for cutting down back slopes and other similar operations which heretofore have been impossible of performance, or difficultly performable.

In my improved structure, a side thrust chain 76 is trained around a pair of sprocket gears 77 and 78 suitably secured between the transverse members 41 and 42 and transversely aligned with respect to each other. One of the links of the chain is connected to a carriage 81 having a plurality of wheels 82-82 riding upon the I-beams as on a track. Movement of the side thrust chain will therefore drive the carriage 81 either to the left or right along the I-beams depending upon which direction the chain is turned. I provide mechanism for driving this chain from the central power source and this mechanism will now be described.

The sprocket gear 77 is keyed to a shaft 83 disposed longitudinally of the frame and journaled in a supporting bracket. One end of the shaft 83 has secured thereon a worm gear 84 which meshes with a worm 85 on a shaft 86 suitably journaled in said supporting bracket. The upper end of this shaft is provided with a bevel gear 87 meshing with a bevel gear 88 which is keyed or otherwise secured to a small shaft 89 connected by a universal joint 91 with a drive shaft 92. This

drive shaft extends rearwardly for connection to the central power source on the rear of the grader. Means (not shown) is provided for turning this shaft in either direction so as to 5 drive the carriage through the gearing and chain shown either to the right or left.

I provide an improved connection between the carriage and the drawbar. A short pin 96 is secured by a nut 97 to the carriage so as to 10 depend vertically therefrom and is pivotally connected at 98 to a link 99. This link is connected to the drawbar in a novel manner whereby an unusual result takes place and this mounting will now be described.

15 In a preceding portion of the specification, certain transverse brace members were described as constituting a part of the drawbar frame. The rearmost of these, designated by the reference character 101, is secured slightly 20 to the rear of the links connected to the crank mechanism. It is secured to the Z-bars or longitudinal members of the drawbar and has end extensions 101a and 101b respectively forming a part thereof and extending to right 25 and left of the Z-bars. While the connection to the link 99 may be made at either side of the drawbar, the position which would be considered as normal is at the left side and for this reason the drawings and description 30 disclose this arrangement.

A channel extension 102 is secured by nuts and bolts 103—103 to the extension 101a of the transverse brace. A pair of bracing members 104 have one end thereof secured to the 35 channel extension 102 by means of nuts and bolts 106—106 and the other ends thereof secured to the transverse brace member 101 by nuts and bolts 107—107. These brace members are of general arcuate shape so as to 40 extend over the top of the Z-bar 18. Bolts and nuts 108—108 are provided to secure the bracing members to the Z-bars and brace the entire extension assembly. On the larger size 45 of graders, I also provide a pair of bracing plates 109—109 suitably secured between the channel extension 102 and the end of the transverse brace member 101.

At the extremity of the channel extension, there is a bracket 111 secured thereto by bolts 50 112 and having a longitudinal aperture extending therethrough, the axis of which is at an acute angle to the plane of the channel extension. A bolt 113 has its shank extending through this aperture and is secured 55 therein by a suitable nut 114. Bolt 113 has a yoke at its upper end and is adapted to cooperate with a single yoke provided on the depending end of the link 99 whereby a suitable arrangement of pivots and the use of an 60 intermediate member, a proper universal joint 116 is provided.

As previously noted, the channel extension 65 102 is normally carried on the left side of the drawbar. The reason for this is that with the usual manipulation of the mold

board, this position permits the grader to work along the right side of a road and hence move along with whatever traffic might possibly be on the road; or where a 70 number of road building machines are working in the same vicinity, the usual right hand traffic rule can easily be followed. It may happen however, that an advantage 75 will be secured by having the extension on the right side of the drawbar. For this reason, I provide suitable apertures in the right side of the transverse member 101 so that the entire extension assembly may be very easily and readily shifted. The connection between 80 the extension assembly and the drawbar proper being by means of easily controlled nuts and bolts, it is obvious that with holes already provided in the proper places on the drawbar the change can be expeditiously 85 made.

In order to make the details and advantages 90 of this construction clearer to those skilled in the art, I may point out that the principal advantage of this reversible construction which I have found in my experiments up to 95 the present time, is in operating on the back slope. With the present type of grader, the mold board may be brought to practically vertical position outside the line of draft of the grader and a substantially vertical wall 100 may be formed along the right side of the road. If this wall were to be cut on the right side of the road at all times, great difficulty 105 might be experienced in hilly regions because it would sometime be necessary to work uphill. In this case the right side of the road can be worked down a grade with the parts in the position shown in the drawings. When the right side is completed, the parts are changed to the position shown in dotted lines 110 (Fig. 3) and then the left side of the road can be worked down hill. In this way the grade is taken advantage of and in no respect will it become an obstacle.

The details of the grader improvements 115 are not necessarily as pictured and described herein, and the scope of the invention is defined in the appended claims.

What I claim as new and desire to secure by United States Letters Patent is:

1. In a road grader, a main frame having a hollow front post, a drawbar having its front end extending into said post and means for reciprocating the front end of the drawbar vertically within said post.

2. In a road grader, a main frame having a front post with a vertical opening therein, a drawbar having a support at the front thereof extending into the post through said vertical opening and means for shifting said support vertically therein to raise or lower the front end of the drawbar.

3. In a road grader, a main frame with a hollow vertically disposed front post, a drawbar suspended below the frame, a universal 130

joint connection between the frame and drawbar disposed within said hollow post, and means for raising and lowering said joint within said post to alter the position of the front end of the drawbar.

5. In a road grader, a main frame with a vertically disposed hollow post at the front end thereof, a drawbar suspended below the main frame having a ball disposed at the 10 front end thereof and extending into the post, a block forming a socket for the ball also disposed within the post, and means for raising and lowering the block in the post to alter the vertical position of the front end 15 of the drawbar.

5. In a road grader, a main frame with a vertically disposed hollow post at the front end thereof with a vertical runway therein, a drawbar suspended beneath the frame with 20 a ball at the front end thereof extending into the post, a block forming a socket for said ball supported in the runway, a gear carried by the block, a rack disposed within the post, and means for turning the gear with respect to the 25 rack for moving the block vertically within the post to alter the position of the front end of the drawbar.

6. In a road grader, a main frame having a hollow vertically disposed front post, a 30 drawbar suspended below the frame with a ball at the front end thereof, a block having a socket for holding the ball to form a substantially universal joint, a vertical rack carried by the post on the inside thereof, a 35 worm meshing with the rack and rotatably carried by the block and means for rotating the worm with respect to the rack to move the block along the axis of the post to alter the position of the front end of the drawbar.

7. In a road grader, a main frame having a hollow front post, a cover therefor, a drawbar having its front end projecting into the post and mechanism carried by the post and 45 cover for reciprocating the front end of the drawbar vertically.

8. The combination defined in claim 7 wherein said reciprocating mechanism is assembled partly in the post and partly on the 50 cover, the various portions of the mechanisms being brought into final operable relationship by the application of the cover to the post.

9. In a road grader, a main frame having a hollow front post with a cover at the front 55 thereof and a longitudinal opening at the rear, a drawbar suspended below the frame with the front end thereof extending through the opening into the post, a block within the post forming a support for the drawbar, a 60 rack carried by the cover on the inside thereof, a worm carried by the block and meshing with the rack on the cover, and means for turning the worm to adjust the position of the block along the axis of the post.

65 10. In a road grader, a main frame having

a hollow front post with a longitudinal opening at the rear thereof, a drawbar suspended from the main frame and having a ball at the front end thereof extending through the opening into the post, a block forming a 70 socket for the ball and vertically reciprocable with respect to the post, a rack on the inside of the post, a vertically disposed worm carried by the block and meshing with the rack, a rotatable vertical shaft slidably supporting the worm, and means for rotating the shaft to cause the block to move vertically with respect to the post.

11. In a road grader, a main frame with a hollow front post, a cover for the post having a rack on the inside thereof, a vertically disposed shaft journaled to the cover, a worm rotatable with the shaft but slidable with respect thereto and meshing with the rack, a drawbar suspended beneath the frame and having a ball at the front end thereof extending into the hollow post, a block within the post forming a socket for the ball, and a connecting means between the block and said worm for imparting to the block, vertical movement of the worm incident to the operation of the shaft.

12. In a road grader, a main frame with a hollow front post, a cover for the post having a rack on the inside thereof, a vertically disposed shaft journaled to the cover, a worm rotatable with the shaft but slidable with respect thereto and meshing with the rack, a drawbar suspended beneath the frame and having a ball at the front end thereof extending into the hollow post, a block within the post forming a socket for the ball and having upper and lower pairs of projections extending around the shaft and supporting the worm between the same, and means for imparting rotary movement to said shaft to move the block vertically within the post.

13. In a road grader, a main frame with a hollow front post, a cover for the post having a rack on the inside thereof, a vertically disposed shaft journaled to the cover, a worm rotatable with the shaft but slidable with respect thereto and meshing with the rack, a drawbar suspended beneath the frame and having a ball at the front end thereof extending into the hollow post, a block within the post forming a socket for the ball and having upper and lower pairs of projections extending around the shaft and supporting the worm between the same, a drive shaft horizontally journaled at the top of the post and a bevelled gear connection between the drive shaft and said first mentioned shaft to move the block vertically within the post.

In witness whereof, I hereunto subscribe my name this 7th day of May, 1928.

WILLIAM J. SCHLACKS.
